CLAIM

The ornamental design for a combined transmitter and receiver for locating children, as shown and described.

DESCRIPTION

FIG. 1 is an exploded front elevational view of the combined transmitter and receiver for locating children showing my new design;

FIG. 2 is an exploded rear elevational view thereof;
FIG. 3 is an exploded left side elevational view thereof;
FIG. 4 is an exploded right side elevational view thereof;

FIG. 5 is a top plan view thereof, with the broken line showing for illustrative purposes only and forming no part of the claimed design; and,
FIG. 6 is a bottom plan view thereof.

FIG. 1

FIG. 2

FIG. 3

FIG. 4
